JAMES MULARKEY, OF KANSAS CITY, MISSOURI, ASSIGNOR TO JAMES P. SPRAGUE,
OF KANSAS CITY, MISSOURI.

BUILDING-PARTITION.

1,110,708.

Specification of Letters Patent. Patented Sept. 15, 1914.

Application filed April 15, 1913. Serial No. 761,186. Renewed January 29, 1914. Serial No. 815,284.

To all whom it may concern:

Be it known that I, JAMES MULARKEY, a citizen of the United States, residing at Kansas City, in the county of Jackson and State of Missouri, have invented certain new and useful Improvements in Building-Partitions; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to building partitions, and more particularly to the construction of studding for use in such partitions and the combination of plaster board therewith, the principal object of the invention being to provide a simple and economical arrangement of the plaster board and means for attaching same to studding, so as to not only provide a simple, substantial and economical structure, but to facilitate the application of the plaster board to the studs and insure its rigid application thereto.

In accomplishing this object I have provided improved details of structure of studding and a plaster board fastener, the preferred form of which is illustrated in the accompanying drawings, wherein—

Figure I is a perspective view of part of a partition constructed according to my invention. Fig. II is a horizontal section of same. Fig. III is a detail elevation of part of the studding, showing the fastening member. Fig. IV is a detail perspective of a fastening member.

Referring more in detail to the parts: 1 and 2 designate the upper and lower floors of a building between which a partition is to be erected. Fixed to the floors 1 and 2 are fastening channel irons 3, and contained within the channel irons, and extending vertically therebetween, are studs 4 which may also be constructed of channel iron, the preferred construction comprising two channel members arranged back to back, and permanently connected by rivets, or the like, 5.

In order to provide simple and economical means for attaching the plaster board to the studding, I install fastening members between the members of the studding when the latter is constructed, such fastening mem-

bers preferably comprising sheet metal strips having pointed ends adapted for penetrating plaster board, so that when the latter is applied to the edges of a stud and penetrated by the points the protected ends 60 of the latter may be folded back onto the board to hold same to the studs, and when the board is applied to the studs in abutment against the projecting portions of the fasteners, the latter may be bent over to 65 clamp the board in place. In order to better adapt the fasteners for such use I prefer to provide projecting ends of the fasteners with laterally turned and pointed lips 6 which are adapted to penetrate the board 70 when the fasteners are turned thereagainst.

It is a well known fact that in building construction most partitions are set on sixteen inch centers, *i. e.*, the studs are sixteen inches apart. It is also well known that 75 each plaster board, lath, or the like, is adapted to overlie more than one stud. In using plaster board, of say thirty-two inches in length, the ends of the board may be applied to alternate studs. When one 80 stud is covered by the central portion of the board, the ends of the board may be fastened by turning the ends of the fastening members thereover and pushing the lips 6 thereinto, and the center portions of the 85 board may be attached to the covered stud by pushing the board against the fasteners until the latter penetrate the board and then turning the projected ends of the fastener over and against the outer face of the board, 90 as illustrated in Fig. I.

It is quite an advantage in partitions of this kind to have the joints of the boards broken, *i. e.*, the ends of the boards on one side of the partition terminate at the center of the board 95 on the opposite side, and inasmuch as most of the studs are set on the same centers I find it convenient and economical to construct the fasteners with a view to fastening the boards to the studs in such broken joint arrangement. To this end I prefer to construct back fastener with a straight pointed lip 7 at one end, and paired lips 8 at the opposite end, with the paired lips provided with the sharpened laterally 100 turned point 6. With the fasteners constructed in this manner the single points of the fasteners are all projected from the same side of a stud and the double points from the opposite side so that when the stud is 110

erected in a partition the studs may be arranged alternately so that ends of the plaster board on one side will abut against fasteners on alternate studs and be penetrated by the single lips of a fastener on an intermediate stud, the arrangement on the opposite side of the partition being the same but offset to provide the broken joints mentioned.

10 In erecting a partition of this improved type the studs which have been previously made up, with the fasteners fixed therein, are erected in the partition with the single and double pointed faces alternating, as 15 illustrated in the drawing. Plaster board is then applied to the partition with the ends of the board abutting against the double fasteners on alternate studs, and the central portion of the board penetrated by the 20 single points of the intermediate stud, all of the single points and one of the double points on each end fastener being turned over onto the board to hold the latter in place. After the board has been set on 25 one end, or simultaneously with such setting, a board is applied to the opposite side of the partition in broken joint arrangement so that the single and double studs may 30 cooperate to hold the board in place and in the staggered arrangement just described.

It is apparent that by having the double points for fastening the ends of the boards, two boards may be brought into end abutment against the fasteners and one point of 35 the fastener turned over one of the boards and the other point into the opposite direction over the other board, the pointed lips on the ends of the double fasteners being projected into the board to hold same in 40 place.

It is apparent that studding constructed according to the above description is not only simple and economical to manufacture, and is easily transported and erected in a 45 building, but when erected obviates the necessity for other devices for fastening the boards in place.

Having thus described my invention, what I claim as new therein, and desire to secure 50 by Letters-Patent, is:—

1. In a partition, studs comprising a first series of alternate studs having a plurality of prongs projecting therefrom on the same side of said partition, and a second series of 55 alternate studs intermediate said first series having prongs projecting therefrom on the same side of said partition as the prongs on said first series of studs and plaster board overlying said studs, said boards having 60 their ends abutting against the prongs on

said first series of studs and their body portions penetrated by said prongs on said second series of studs, and all of said prongs having their ends bent over the face of said boards, for the purpose set forth. 65

2. In a partition, studs comprising alternate studs having a plurality of paired prongs projecting therefrom on the same side of said partition and intermediate studs having prongs projecting therefrom 70 on the same side of said partition as said paired prongs, and plaster board overlying said studs, said boards having their ends abutting against said paired prongs and their body portions penetrated by said 75 prongs on said intermediate studs, and all of said prongs having their ends bent over the face of said boards, for the purpose set forth.

3. In a partition, the combination with 80 studs having attaching members projected therefrom, the attaching members on one stud having paired prongs projected from one face and single prongs from the opposite face, the arrangement of the prongs on adjacent studs being reversed, plaster boards applied to said studs and having their body portions penetrated by the single prongs and their ends locked by members of the double prongs on alternate studs, the ends of the 85 boards on one side of the partition being in transverse alinement with the central portions of the boards on the opposite sides of the partition, substantially as and for the purpose set forth. 90

4. In a partition, a stud comprising attaching members, each formed from a single piece of sheet metal, having one end slit to provide prongs, and the opposite end having a single pointed prong, the paired 100 prongs having laterally turned and spaced anchoring lips and the single prongs being flat, for the purpose set forth. 95

5. In a partition, a stud comprising attaching members, each formed from a single 105 piece of sheet metal, having one end provided with prongs having laterally pointed lips extending in opposite directions, and the opposite end of the strip having a single pointed but unbent prong, all of the lipped 110 prongs being extended from one face of the stud and the single prongs from the opposite face, substantially as set forth.

In testimony whereof I affix my signature in presence of two witnesses.

JAMES MULARKEY.
